RADIO SYSTEM

Filed Nov. 23, 1927

UNITED STATES PATENT OFFICE

LESTER J. WOLF, OF SOUTH BEND, INDIANA, ASSIGNOR TO WESTINGHOUSE ELECTRIC & MANUFACTURING COMPANY, A CORPORATION OF PENNSYLVANIA

RADIO SYSTEM

Application filed November 23, 1927. Serial No. 235,374.

This invention relates to radio systems, and particularly to provisions for maintaining, at a predetermined frequency the energy broadcast from a sending station.

5 As explained in my copending application, Serial No. 238,823, filed December 9, 1927, assigned to the Westinghouse Electric & Manufacturing Company, it is possible to impress upon a radio sending station, a frequency determined at a distance. It is also possible to maintain the frequency of a broadcasting station constant within narrow limits by means of a master oscillator controlled by a piezo-electric crystal.

10 15 It is an object of my invention to combine these two methods of control and provide means whereby, if one method fails, the other will be automatically substituted.

It is a further object of my invention to 20 provide a grid-biasing device controlled by the presence or absence of oscillations in one frequency-controlling arrangement, for blocking the crystal-controlled tube when the frequency arrangement just mentioned is operative and removing the blocking potential at other times.

25 Other objects of my invention and details of the structure will be evident from the following description and the accompanying drawing, in which the single figure is a diagram of the circuits and apparatus.

In the figure, the alternating-current source 1 is any source of low frequency. It may, for example, be the frequency obtained by a special communication channel from a distant 30 frequency-controlling device.

If the frequency of the source 1 is too low for broadcasting purposes, it may be impressed upon a frequency multiplier including as many steps as are necessary to bring it to the frequency desired for radiation. One stage of the multiplier is illustrated on the drawing. It comprises a vacuum tube 2, the grid of which is supplied from the source 35 40 45 1. The plate current of the tube 2 contains

a parallel-resonant circuit 3, tuned to the frequency of the source 1 and a parallel-resonant circuit 4 tuned to the frequency of a harmonic thereof.

The tube 5 is an amplifier, the grid of which 50 is connected through the condenser 6 to a point between the circuits 3 and 4. A grid leak for the tube 5 is provided through the resistor 7 and a grid-biasing battery 8. Although only a simple amplifier 5 is illustrated, 55 any desired number of amplifiers arranged in cascade may be used.

An inductor 10 and condenser 11 serve to couple the amplifier 5 to a tuned circuit 12, from which a connection 13 extends to the 60 transmitting device. The transmitting device may be a power amplifier or any other arrangement, the frequency of which is controlled by the frequency in the circuit 12.

A vacuum tube 14 is equipped with the frequency-determining piezo-electric crystal 15. 65 The circuits associating the tube 14 and the crystal 15 are illustrative only. Many circuits by which a vacuum tube generator can be controlled by crystal are well known and 70 any suitable circuit may be used. The grid of the tube 14 is provided with a grid leak comprising a resistor 16 and a biasing device by which a portion of the potential of the battery 8 is impressed on the grid. 75

The side of the condenser 6 toward the plate circuit of the tube 2 is connected, through a condenser 17, to the anode of a rectifier 18. Said anode is connected through a radio-frequency choke coil 19 to the grid of 80 the tube 14.

In the operation of the device, the oscillations from the source 1, whether this source be a receiving set controlled by a frequency-determining device at a distant station, a 85 tuning fork at the illustrated station, or any other form of frequency-determining device, are impressed upon the tube 2 and amplified thereby. A harmonic of the amplified oscillations is impressed upon the tube 5. The 90

high-frequency oscillations are amplified either by the tube 5 alone or, if several stages of amplification are provided, by each stage thereof, and so reach the tuned circuit 12 and maintain it in oscillation.

The battery 8 impresses upon the grid of the tube 5 so high a negative bias, that this tube is nonconducting except during those portions of each cycle of the frequency delivered over the condenser 6, which are sufficiently positive to overcome the effect of the battery 8. The energy delivered by the tube 5, either directly to the circuit 12 or to the next stage of the amplifier, will consist, therefore, of separated impulses, the frequency of which is determined by the frequency of the source 1. They will maintain the circuit 12 in oscillation and the decrement of the circuit 12 is sufficiently small to cause the oscillations impressed thereby upon the transmitter, to be substantially uniform.

The connection through the condenser 17 delivers an alternating current to the rectifier 18. The current will pass through the rectifier when a positive potential is impressed upon the anode thereof, but will not pass in the opposite direction. A charge will, therefore, accumulate upon the condenser 17, causing the right hand electrode thereof to become negative.

The negative potential from this condenser will be impressed, through the choke coil 19, upon the grid of the tube 14. The individual fluctuations at the frequency of the circuit 4 will not be impressed upon the grid of the tube 14 because of the choking action of the coil 19. The condenser 17 tends to discharge over a path through the choke 19, the resistor 16, the potentiometer at the battery 8, the filament leads, the B battery and the inductor of the circuit 4. The leakage over this path is sufficiently slow, because of the high resistance of the grid leak 16, to permit the accumulated charge on the condenser 17 to supplement the potential impressed upon the grid of the tube 14 by the battery 8.

The potentiometer associated with the battery 8 permits the bias of the tube 14 to be adjusted. Preferably this bias, when the condenser 17 is discharged, is only slightly negative since a vacuum tube oscillation generator of this type works most effectively with a slightly negative grid.

When a charge has accumulated upon the condenser 17, the grid of the tube 14 is strongly negative. It, therefore, produces a blocking action and prevents the oscillation-generator 14 from producing any oscillations while the source 1 is delivering oscillations to the tube 2.

If from any cause, the oscillation-generator 1 should cease to deliver oscillations, the charge will cease to accumulate upon the condenser 17. The leakage action of the circuit through the resistor 16 will then become

effective and the grid of the tube 14 will assume the potential derived from the battery 8. This will cause the tube 14 to generate oscillations.

The frequency of the oscillations generated by the tube 14 is determined by the crystal 15. Preferably, this crystal is so chosen that the frequency delivered from the tube 14 to the circuit 12 is very nearly like that delivered from the tube 5 to the circuit 12. The broadcasting station, therefore, will continue to send out radiations of nearly the same frequency when the source 1 is inoperative as it sends when controlled by the source 1.

The choke coil 19 prevents the oscillations generated by the tube 14 from being impressed upon the input of the tube 5. Moreover, because of the strongly negative bias of the tube 5, such oscillations as do reach the condenser 6 from the tube 14 will be insufficient to produce any result in the output of the tube 5. If, therefore, the source 1 and the tube 14 should ever be both oscillating at once, a beat note will not result, but the circuit 12 will be controlled by the source 1.

It will, therefore, be evident that the system herein shown will control the frequency of the broadcasting station in accordance with the frequency from the source 1, as long as said source is operative. The amplifier tube associated with the source 1 insures that when the source 1 is operated even approximately near to its normal amplitude, the voltages impressed upon the grid of the tube 5 are sufficient to overcome the effect of the battery 8 and render the tube 5 conductive, at least once during each cycle of the harmonic selected by the circuit 4.

When the oscillations impressed on the grid of the tube 5 are sufficient to accomplish this result, the charge developed upon the condenser 17 is ample to produce the blocking effect upon the tube 14. On the other hand, when the tube 14 is producing oscillations, so small a fraction thereof will pass the choke coil 19, that they will be insufficient to overcome the biasing effect of the battery 8 and the tube 5 will remain non-conductive. The oscillations produced in the circuit 12 cannot be propagated through the tube 5 because they reach it in the non-conductive direction. Dissipation of the energy from the tube 14, either in the circuits to the left of the choke coil 19 or in the amplifier connected with the tube 5 is, therefore, unlikely to occur.

While I have described and illustrated a single embodiment of my invention, many variations thereof will be evident to those skilled in the art, and the omission of them from the description is not to be considered a limitation. No limitation is intended except such as is required by the prior art or indicated in the accompanying claims.

I claim as my invention:

1. In a radio system, a transmitting de-

- vice, a source of low-frequency control energy, a frequency multiplying means for producing a high frequency therefrom and for controlling said transmitting device by 5 said high frequency, a second source of high frequency, means for controlling said transmitting device from said second source and means responsive to the first source for preventing the second source from producing 10 oscillations.
2. In a radio system, a transmitting device, a master source of periodic energy, governing means for controlling the frequency of the energy in the transmitting device in 15 accordance with the frequency from said master source, a second source of periodic energy and connections whereby it may control the frequency of the energy in the transmitting device, and means for preventing 20 said second source of periodic energy from producing oscillations whenever the energy delivered from the master source exceeds a predetermined minimum, said governing means including a device for preventing energy from the master source from affecting 25 the transmitting device when the energy from the master source is insufficient to render said preventing means effective.
3. In a radio system, a transmitting device, two sources of frequency-controlling energy, means for preventing the generation of oscillations by one of said sources, and means for preventing oscillations produced by the other source from controlling the frequency 35 at the transmitting device, and means whereby each of said preventing means is effective only when the other is ineffective.
4. In a radio system, a transmitting device, two sources of frequency-controlling energy, means for preventing the generation of oscillations by one of said sources, and means for preventing oscillations produced by the other source from controlling the frequency at the transmitting device, and means 40 controlled by the magnitude of the energy from one of said sources for determining which preventing means shall be effective.
5. In a signaling system, a transmitting device, a source of frequency-determining energy therefor, a second source of frequency-determining energy therefor, means responsive to energy from the first-mentioned source for rendering the second-mentioned source ineffective, and means whereby 45 the first-mentioned source is prevented from controlling the frequency of said transmitting device if the energy delivered from said source falls below a predetermined minimum.
6. In a signaling system, a transmitting device, a source of frequency-determining energy therefor, a second source of frequency-determining energy therefor, and means responsive to energy from the first-mentioned source for so controlling the oper- 50 55 60 65 70 75 80 85 90 95 100 105 110 115 120 125 130
- ation of the second-mentioned source that said sources cannot be simultaneously effective to determine the frequency of said transmitting device.
7. In a radio system, two controlling devices for determining a carrier-wave frequency and means responsive to energy delivered by one of said devices for preventing the simultaneous control of the carrier-wave frequency by both of said devices.
- In testimony whereof, I have hereunto subscribed my name this 21st day of November, 1927.
- LESTER J. WOLF.
